UNITED STATES PATENT OFFICE.

WILLIAM H. SNELSON, OF CHICAGO, ILLINOIS, ASSIGNOR OF SEVEN-SIXTEENTHS TO GEORGE JUDGE, OF SAME PLACE.

PULLEY-SHEAVE.

SPECIFICATION forming part of Letters Patent No. 312,668, dated February 24, 1885.

Application filed July 1, 1884. (No model.)

To all whom it may concern:

Be it known that I, WILLIAM H. SNELSON, of Chicago, county of Cook, and State of Illinois, have invented certain new and useful 5 Improvements in a Pulley-Sheave, of which the following is a full, clear, and exact description, that will enable others to make and use the same, reference being had to the accompanying drawings, forming a part of this 10 specification.

This invention relates more especially to improvements in that class of sheaves having a grooved periphery for the purpose of adapting the same to carry the wire rope employed 15 in the cable traction system for moving street-cars. It is also obvious that a pulley or sheave of this character may be used for various purposes.

The object is to provide a carrying pulley 20 or sheave that will reduce the friction and lessen the wear on both the cable and sheave, and also prevent the face or cable-bearing surface of sheave being affected by corrosion, as the sheaves used in street-car service are 25 usually placed below the level of the ground surface, and are as a matter of course more or less in the water.

The nature of this invention consists in forming the body of the pulley or sheave of 30 glass, which is properly supported and clamped between metallic flanges. It also consists of certain novel features in the construction and manner of securing the different parts together, as will be hereinafter more fully set 35 forth in detail.

Figure 1 is a side elevation of a pulley or sheave embodying my improved features; Fig. 2, a partial transverse section of the same. Figs. 3, 4, and 5 are modifications.

Referring to the drawings, A A' represent 40 the inclosing flanges or sides, B the arms, C the hub, and D the glass body. The body D is composed of glass, and ordinarily has beveled sides, as shown in Fig. 2, the broadest 45 or base part resting on the annular rim a, which is cast on the ends of the spider-arms B, together with the one side flange, A, the companion flange, A', being formed independent and detachably secured in relation to the other 50 parts. The inclosing-flanges A A' are beveled on the inner faces to correspond to the body

D. The body D is provided on the periphery with the annular groove a', for the reception of the cable. For small sheaves the glass body or center will usually be formed as a 55 whole; but for large sheaves or pulleys practical working may require the same to be prepared in segmental sections. This form of construction will also facilitate repairs and be more economical, as a fractured segment 60 can be conveniently replaced by another without having to replace the body as a whole.

The detachable or loose flange A' is secured in position with relation to the other parts by means of the series of screw-bolts E, which 65 pass through the glass body, the threaded ends engaging with the correspondingly-threaded apertures a² in the flange A', while the opposite or headed ends are countersunk in the companion flange, A. By this arrangement 70 all the parts are securely and firmly clamped together, leaving no projecting bolt ends or nuts to be in the way, and also readily permitting of the structure being taken apart for repairs. The flange A' is also provided with the annular groove a', which receives and engages with 75 the edge of the rim a, and serves to assist in strengthening and in retaining these parts in their proper relative position.

The series of openings a⁴ in the flanges A A' 80 provide means for keeping the sheaves in balance by simply filling the same with lead or some suitable plastic substance that is easily inserted or removed, as may be required. These 85 openings are gradually contracted outward from the inner sides of the flanges, as shown in Fig. 3, whereby the filling is more surely retained.

The angular extended ledges b b' on the flanges A A' serve to guard against the liability of the cable getting off the sheaves. The 90 contacting surfaces of the glass and metal will be covered with white lead or some similar substance, for the purpose of forming tight joints and excluding the moisture.

The modification, Fig. 3, shows a double 95 pulley or sheave, the glass body being provided with two grooves, the metallic flanges or inclosing sides having independent hubs. In this case the contacting surfaces of the 100 flanges and glass body are straight instead of beveled, and are clamped together by screw-

bolts, as already described. The glass body is provided on each side with the annular projecting bead d , which engages with corresponding grooves in the inclosing flanges.

5 Fig. 4 shows the glass body with annular shoulders d' , the inclosing flanges having beads engaging with said shoulders for the purpose of assisting in retaining these parts together.

10 Fig. 5 shows a sheave or pulley wholly of glass, which may be rigidly secured to its shaft by the use of sulphur or other suitable cement composition. If the pulley is required to rotate loosely on a stationary shaft, the eye through the pulley should be bushed with Bab-
15 bitt metal or other material that will provide a suitable bearing. This pulley is provided on its periphery or face with the usual carrying-groove, the face sloping inward toward said groove, so that the cable will not be so
20 likely to jump off. This pulley is also provided on each side with the annular grooves d^2 d^3 , which in turn are provided at regular intervals with the cupped-out cavities or recesses

d^4 . (Indicated by the dotted lines.) These cavities may be of any particular shape, and 25 are designed to receive and hold some substance to retain the pulley in proper balance.

Having thus described my invention, what I claim, and desire to secure by Letters Patent, is—

30 1. A pulley-sheave having a body and bearing-face composed wholly of glass, substantially as described.

2. A pulley-sheave consisting of the hub C, the arms B, the rim a, the rigid flange A, 35 the glass body D, the detachable flange A', provided with the annular groove a^1 , and the clamping screw-bolts E, substantially as described.

3. A pulley-sheave having the sides or 40 flanges provided with the openings a^1 , substantially as and for the purpose set forth.

WILLIAM H. SNELSON.
